UNITED STATES PATENT OFFICE

2,580,520

TORQUE TUBE BRACKET ASSEMBLY FOR
CLOTHES WRINGERS

Orville F. Couchot, De Land, Fla.

Application August 5, 1949, Serial No. 108,806

8 Claims. (Cl. 68—274)

1

This invention relates to a bracket assembly for supporting a clothes wringer above a laundry tub for swivel movement relatively thereto and provides means for tilting a part of the assembly for positioning the clothes wringer in substantially a horizontal plane to prevent sagging of the clothes wringer at its outer end and for maintaining the drive shaft of the clothes wringer in an upright position.

More particularly, it is a primary object of the present invention to provide an adjustable bracket assembly for eliminating a sagging condition of a clothes wringer for thereby maintaining the drive shaft in a proper position relatively to the gear case and gear head of the wringer so that the drive shaft will be correctly disposed to assure proper meshing engagement of the gears by which the shaft is driven and by which the clothes wringer is driven by the shaft.

Still a further object of the invention is to provide an adjustable assembly of the afore-described character of extremely simple construction, which is capable of being readily applied to conventional clothes wringers, which may be quickly and easily installed and which is extremely efficient and durable for accomplishing its intended purpose.

Various other objects and advantages of the invention will hereinafter become more fully apparent from the following description of the drawing, illustrating a preferred embodiment thereof, and wherein:

Figure 1 is a side elevational view of a laundry tub showing a clothes wringer supported thereby by means of the torque tube bracket assembly;

Figure 2 is a top plan view thereof;

Figure 3 is an enlarged fragmentary side elevational view partly in vertical section of the invention;

Figure 4 is an enlarged fragmentary vertical sectional view partly in side elevation of a portion of the invention, and

Figure 5 is a horizontal sectional view taken substantially along a plane as indicated by the line 5—5 of Figure 3.

Referring more specifically to the drawing, for the purpose of illustrating one preferred application and use of the torque tube bracket assembly, designated generally 6 and comprising the invention, a conventional type of laundry tub is illustrated in the drawing and designated generally 7, said tub being of the type commonly used in self-service laundries and which includes four partitions 8 which divide the tub into four separate compartments 9, each of which is open

at its top and may be provided with an agitator 10. One of the partitions 8 is provided at its inner end with diverging portions 11 which combine with portions of the two partitions disposed at a right angle thereto to form a passage 12 of substantially triangular shape which extends through the tub 7 from top to bottom thereof. The tub 7 is supported in an elevated position by depending supporting legs 13 and has a gear case 14 mounted on the underside thereof and supported by a flange 15 on said gear case which is secured by fastenings 16 to the bottom of the tub 7 beneath the passage 12. A drive shaft 17, which is driven through gearing within the gear case 14 and from a suitable power source, not shown, extends upwardly from said gear case through the passage 12 and has its upper end extending into the gear head 18 of a clothes wringer 19 which is disposed above the tub 7. The gear head 18 is swivelly mounted on the upper end of the shaft 17 so that the wringer 19 can be swung in substantially a horizontal plane through a complete circle in either direction for positioning the wringer over any one of the tub compartments 9 or over any one of the partitions 8. Suitable bevelled gearing, not shown, forms a driving connection between the drive shaft 17 and the shaft connected to the rollers of the wringer. The gear head 18 is provided with a depending tubular wringer post 20 which surrounds a portion of the drive shaft 17 and which extends downwardly from the gear head and terminates above the top of the tub 7. The parts 7 to 20, inclusive, constitute no part of the present invention but have been illustrated and briefly described merely to afford a better understanding of the torque tube bracket assembly 6, comprising the invention and which will hereinafter be described.

The weight of the wringer 19 normally causes it to sag above the tub 7 so that it is inclined downwardly from the gear head 18 toward its outer end which is inconvenient to the user and which additionally causes a tilting of the drive shaft 17 so that the gears by which the shaft is driven at its lower end and by which the shaft drives the wringer at its upper end are displaced out of proper meshing relationship thereby producing unnecessary wear and damage to the wringer parts. Furthermore, the weight of clothing supported by the wringer increases this sagging thereof and tilting of the drive shaft.

Accordingly, the present invention is intended to provide a means for eliminating the sagging of the clothes wringer and the displacement of

its drive shaft 17 from an upright position. The torque tube bracket assembly 6 includes a bracket tube 21 which extends through the passage 12 from adjacent its lower end to a short distance above the top surface of the tub 7. The bracket tube or pipe 21 is secured in the passage 12 and in an upright position by a plurality of fastenings 22 which are secured to the partition portions 11 and to the other wall of the passage 12, formed by the other two partitions 8, which are disposed at a right angle to the partition provided with the portions 11. A reducer 23 has its restricted end 24 engaging the upper end of the tubular bracket 21 and is permanently secured thereto by a weld 25. The tubular bracket 21 terminates adjacent the upper end of the restricted lower portion 24 of the reducer 23. The enlarged, upper portion 26 of the reducer 23 is provided with circumferentially spaced threaded openings 27 through each of which threadedly extends an adjusting or set-screw 28, said screws extending inwardly with respect to the reducer 23.

A torque tube 29 is loosely disposed within the tubular bracket 21 and has its lower end extending into a socket 30 of the gear case 14, by which said torque tube 29 is supported in substantially an upright position. As seen in Figure 3, the socket 30 is sufficiently large to afford a clearance between its annular wall and the torque tube 29 and the bore of the tubular bracket 21 is likewise larger in diameter than the external diameter of the torque tube 29 to afford a clearance therebetween. The torque tube 29 extends upwardly through the bracket tube 21 and the reducer 23 to a point above said reducer but beneath the normal level of the wringer gear head 18. A collar 31 is secured by welding, as seen at 32, or otherwise in a stationary manner around the torque tube 29 and at a level to be disposed within the enlarged reducer portion 26 and in horizontal alignment with the adjusting screws 28, the inner tapered ends of which engage the periphery of the collar 31 or recesses 33 therein. The lower end of the tubular wringer post 20 is disposed loosely around the upper end of the torque tube 29 and rests upon the upper surface of the collar 31 and is swivelly supported thereon so that the wringer 19 may swing in a circle above the tub 7.

From the foregoing it will be readily apparent that by advancing or retracting the individual adjusting screws 28 the torque tube 29 may be displaced radially relatively to the bracket tube 21 and reducer 23 for eliminating any tilt of the torque tube 29 and for maintaining it in an upright position. As the weight of the wringer 19 and its gear head 18 are supported by the torque tube 29 through engagement of the tubular gear post 20 with the collar 31, the drive shaft 17 is relieved entirely from the weight of the wringer or gear head so that all tendency to displace the drive shaft out of an upright position is eliminated thereby insuring proper meshing engagement of the gear for driving said shaft and by which the wringer is driven thereby and additionally insuring that the wringer 19 will be supported with its longitudinal axis in substantially a horizontal plane and above the tub 7 and free to revolve in a circle thereover. By proper adjustment of the screws 28 any unusual weight to which the wringer 19 might be subjected and which would tend to cause the wringer to sag at its outer end may be compensated for by tighten-

ing certain of the screws 28 and loosening other of said screws.

Various modifications and changes are contemplated and may obviously be resorted to, without departing from the spirit or scope of the invention as hereinafter defined by the appended claims.

I claim as my invention:

1. A torque tube bracket assembly for clothes wringers comprising a bracket tube adapted to extend through a passage in the central portion of a laundry tub and secured thereto in an upright position, a reducer having a restricted lower end secured around the upper end of said bracket tube and adapted to be disposed above the level of the top of the tub, a plurality of circumferentially spaced adjusting setscrews extending threadedly through the enlarged upper portion of said reducer and disposed radially thereof, a torque tube adapted to be supported at its lower end on a gear case disposed beneath the tub and extending upwardly therefrom through the bracket tube and reducer, said torque tube being adapted to loosely accommodate a clothes wringer drive shaft therein and being radially displaceable relatively to the bracket tube, drive shaft and gear case, and a collar disposed around the torque tube and secured thereto, said collar being disposed to be engaged by the inner end of said adjusting screws whereby the adjusting screws will maintain the torque tube in an upright position, and said collar being adapted to provide a support for the lower end of a tubular post which depends from the gear head of a clothes wringer for supporting the clothes wringer on the torque tube.

2. A torque tube bracket assembly as in claim 1, said gear head post being rotatable on said collar and being swivelly disposed around the portion 40 of the torque tube extending above the collar.

3. A torque tube bracket assembly for clothes wringers comprising a tubular bracket member adapted to extend through a laundry tub and rigidly secured thereto in an upright position, a torque tube extending loosely through said tubular bracket and adapted to be supported at its lower end on a gear case for a clothes wringer and being displaceable radially relatively to the tubular bracket and gear case, said torque tube being adapted to loosely accommodate a clothes wringer drive shaft therein, means disposed adjacent the upper end of the tubular bracket for radially displacing the torque tube relatively thereto, and means mounted on said torque tube 45 on which the depending end of a tubular gear head post of a clothes wringer is adapted to be swivelly supported for swingably mounting the clothes wringer and for maintaining it with its longitudinal axis in substantially a horizontal position.

4. A torque tube bracket assembly for clothes wringers comprising a tubular bracket adapted to be fixedly supported in an upright position, a torque tube extending longitudinally therethrough adapted to be supported at its lower end on the gear case of a clothes wringer and providing a housing adapted to loosely accommodate a clothes wringer drive shaft therein, said torque tube being radially displaceable relatively to the tubular bracket and gear case, adjustable means adjacent the upper end of said tubular bracket for displacing the torque tube radially thereof and for maintaining it in adjusted positions relatively to the tubular bracket, and a collar carried by said torque tube and adapted to

support and swivelly mount a depending tubular post of the gear head of the wringer.

5. A torque tube assembly as in claim 4, said torque tube and gear head post forming a housing through which the wringer drive shaft is adapted to loosely extend.

6. A torque tube bracket assembly as in claim 4, said tubular bracket having an enlargement at its upper end in which said collar is loosely disposed, and said means comprising setscrews threadedly engaging said enlargement and extending radially therethrough for engagement with the collar.

7. A torque tube bracket assembly for clothes wringers comprising a tubular bracket member adapted to extend through a laundry tub and rigidly secured thereto in an upright position, a torque tube extending loosely through said tubular bracket and adapted to be supported at its lower end on a gear case for a clothes wringer and being mounted for limited rocking movement on the gear case and within the bracket tube, means disposed adjacent the upper end of the tubular bracket for rocking the torque tube relatively thereto, and means mounted on said torque tube on which the depending end of a tubular gear head post of a clothes wringer is adapted to be swivelly supported for swingably mounting the clothes wringer and for maintaining it with its longitudinal axis in substantially a horizontal 30 position.

8. A torque tube bracket assembly for clothes wringers comprising a tubular bracket adapted to be fixedly supported in an upright position, a torque tube extending longitudinally therethrough adapted to be supported at its lower end on a gear case for limited rocking movement relatively thereto, said torque tube being swingable within the tubular bracket, adjustable means adjacent the upper end of said tubular bracket for displacing the torque tube radially thereof and for maintaining it in adjusted positions relatively to the tubular bracket, and a collar carried by said torque tube and adapted to support and swivelly mount a depending tubular post of the gear head of the wringer.
